THEODORE B. BECHTEL, OF SALEM, OHIO

ELECTRIC FURNACE

Application filed March 21, 1928. Serial No. 263,310.

This invention relates to electric furnaces.

The electric furnace to which the invention applies in particular has helical heating resistors arranged within a heating chamber 5 and supported by refractory insulators or supports.

A furnace of this character is ordinarily employed for the heat treatment of steel or other metal upon which oxid or scale is 10 formed when heated to a certain temperature.

A part of the scale thus formed falls from the metal into the furnace, and, if allowed to accumulate upon the resistor supports, it will seriously impair the efficiency of the resistors 15 by restricting the dissipation of heat therefrom.

If the scale is conductive, an accumulation thereof upon a resistor support will enable the current flowing through a helical or other 20 convoluted resistor carried by that support to be short-circuited or pass direct from one turn of the resistor to an adjacent turn thereof, thereby causing the resistor to burn out within a relatively short time after the scale 25 has accumulated about the same.

The invention has as an object to provide an electric furnace which has high efficiency and which is economical to operate.

Another object is to provide an electric 30 furnace with an insulator or support which will allow a helical or other convoluted resistor to dissipate its heat freely from substantially its entire radiating surface and which will prevent scale or other matter from 35 accumulating about the resistor.

Another object is to provide an electric furnace with refractory insulators or supports which are carried by the wall thereof to support a helical or other convoluted resistor 40 at several points intermediate its ends and which carry means for supporting the resistor intermediate adjacent insulators or supports.

Another object is to provide an electric 45 furnace with helical or other convoluted resistors and supports therefor which may be readily and easily removed and replaced.

According to the invention in one of its aspects, an electric furnace is provided with a 50 resistor support having an open seat which is

shaped longitudinally to retain a resistor therein and shaped transversely to provide a narrow supporting face and inclined faces sloping downward from the supporting face to allow scale or other matter to fall freely 55 from the support and thereby prevent it from accumulating upon the seat and about a resistor arranged therein.

According to the invention in another aspect, an electric furnace is provided with resistor supports which are spaced from each other and carried by the furnace walls to support a resistor at spaced intervals along the same, a seat arranged upon each support and shaped to retain the resistor therein and to 60 prevent accumulation of scale or other matter about the resistor, and means carried by the supports for supporting the resistor intermediate adjacent resistor supports.

According to the invention in another aspect, an electric furnace is provided with a resistor support to support a resistor within the furnace, a seat arranged upon the support and shaped to retain the resistor in position thereon and to permit the free discharge of 75 scale or other matter from around the resistor, and a bracket carried by a wall of the furnace and extending into the support to carry the same.

An electric furnace embodying the invention is illustrated in the accompanying drawings in which the views are as follows:

Fig. 1 is a vertical transverse section through the furnace;

Fig. 2 is a detail view of a resistor support and a bracket for supporting the same;

Fig. 3 is a section on the line 3—3 of Fig. 2;

Fig. 4 is a detail view of another resistor support;

Fig. 5 is a section on the line 5—5 of Fig. 4;

Fig. 6 is a detail view showing a resistor supported throughout its length by means of intermediate supports carried by the supports shown in Fig. 4;

Fig. 7 is a plan view of the intermediate support shown in Fig. 6;

Fig. 8 is a section on the line 8—8 of Fig. 7; and

Fig. 9 is a view similar to Fig. 1 but show-

ing a different method of supporting the uppermost resistor.

Figs. 1 to 3.

The furnace is provided with outer side walls 1, a roof 2, a bottom 3, and a lining 4, all of which constitute the walls of the furnace.

The lining 4 is made of a refractory substance which is capable of withstanding high temperatures.

The side walls of the furnace are provided with a number of side brackets 5 which are embedded in the lining thereof and project inward into a heating chamber 6 formed by the furnace walls.

The brackets 5 are arranged in horizontal rows and each bracket is provided upon its upper edge with a convex seat 7 and upon its inward end with an upward flange or projection 8, both of which are arranged, in alinement with the corresponding seats and projections upon the other brackets in the same row.

The top wall of the furnace carries a number of angular roof brackets 9 which are arranged in rows longitudinally of the furnace and have the vertical legs thereof extended through the roof 2 and embedded in the lining 4 and the horizontal legs thereof arranged within the heating chamber 6.

Each bracket 9 is provided at its upper end with a pin 10 which bears upon the roof 2 to support the bracket, and upon its horizontal leg with a convex seat 11 and an end flange 12 which corresponds to the seat 7 and the flange 8 of the bracket 5.

The seats 11 and the flanges 12 are arranged in alinement with the corresponding seats and flanges on the other brackets in the same row.

The brackets 5 and 9 are ordinarily made of a refractory metal, such as nichrome or other heat resisting substance.

Each of the brackets 5 and 9 carries a refractory insulator or resistor support 13 which has an open slot 14 formed in the bottom thereof and shaped to conform to the seat and end flange upon the bracket, as shown in Figs. 2 to 5.

The slot 14 enables the resistor support to be readily placed in position upon the bracket and be removed therefrom, and the walls of the slot coat with the seat and end flange to position the insulator upon the bracket.

Each resistor support 13 is provided with an open resistor seat 15 to support a helical or other convoluted resistor 16 which is shown as a wire or bar of resistance material wound into a helix.

The seat 15 is shaped to retain the resistor therein by being concave in longitudinal section, and to prevent the accumulation of scale about the same by being convex in transverse section.

The seat 15 is open at its top and has a very

narrow supporting surface which makes substantially a point or line contact with the resistor, thereby enabling the resistor to freely dissipate its heat from substantially its entire radiating surface.

70

The side faces of the seat 15 curve or slope downward from its supporting surface and allow scale to fall freely therefrom, thereby preventing any accumulation of scale upon the seat.

75

The support 13 is provided upon each of its sides with narrow projections or ribs 17 which have the tops thereof arranged in alinement with the supporting surface of the seat 15 and which function as auxiliary or intermediate supports for supporting the resistor upon each side of its point of contact with the seat 15.

80

Each projection or rib 17 is shaped to permit the free discharge of scale from the seat 15 and to provide a narrow top with which the resistor makes substantially a point or line contact.

85

A resistor support 13 may be placed upon the inward part of each bracket 5 and upon the lower part of each bracket 9, and the seats 7 and 11 and the projections 8 and 12 will positively position the supports in horizontal rows and aline each support with the other supports in the same row.

90

Any one of the supports 13 may be readily removed by simply lifting it from its bracket, and may be as readily replaced by simply inserting another support upon the same bracket.

100

The bottom of the furnace may also be provided with resistor supports 13 which are spaced from each other and arranged in rows upon the lining of the furnace bottom.

105

A resistor 16 may then be placed in the seats 15 of the supports in each row and supported thereby in a horizontal position. The resistor is then connected into an electric circuit in the usual manner.

110

Any one of the resistors may be readily removed by simply disconnecting it from the electric circuit and then simply lifting it from the supports by which it is carried.

115

The furnace may be provided with a hearth plate 18 which is made of suitable heat resisting material and supported from the bottom of the furnace by legs or posts 19.

Figs. 4 to 8.

The insulator or resistor support 20 shown in Figs. 4 and 5 is the same as the support 13 except that the projections 17 are omitted from around the seat 15 and an angular projection 21 extends laterally from the lower part of each of its sides at each end thereof.

120

The projections 21 upon each side of the support 20 are adapted to support one end of the elongated intermediate support 22 shown in Figs. 7 and 8.

125

The intermediate support 22 has two side

130

bars 23 which are spaced apart and connected to each other by cross-bars or ribs 24.

Supports 20 may be arranged upon the brackets 5 or 9 in place of the supports 13, 6 and a support 22 arranged between two adjacent supports 20 and carried by the projections 21 upon the adjacent sides thereof to furnish a continuous support for a resistor 16, as shown in Fig. 6.

10 The lower flanges of the projections 21 support the ends of the side bars 23, and the vertical flanges of the projections 21 restrain the support 22 from lateral movement.

The tops of the side bars 23 and the cross-bars 24 are shaped to permit scale to fall freely therefrom and thereby prevent an accumulation of scale about a resistor arranged thereon.

Fig. 9.

20 The uppermost resistor supports, instead of being carried by brackets 9, are shown in this figure as being carried by cross-bars 25 which are made of refractory metal and have the ends thereof embedded in the lining of 25 the side walls.

Each cross-bar 25 is provided at intervals along its length with projections 26 and seats 27 which are similar to the projections 12 and seats 11 on the brackets 9.

30 Each seat 27 has a projection 26 arranged at each end thereof to retain a resistor support 13 or 20 thereon, in which position the resistor support is in alinement with the corresponding resistor supports carried by 35 the other bars 25.

The invention herein set forth is susceptible of various modifications without departing from the scope thereof as hereinafter claimed.

The invention is hereby claimed as follows:

1. An electric resistance furnace, comprising furnace walls forming a heating chamber, helical resistors arranged horizontally in said chamber, refractory resistor supports 45 carried by said furnace walls to support said resistors, an open resistor seat formed on each support and shaped longitudinally to retain a helical resistor therein and shaped transversely to make substantially a line contact 50 with said resistor, and intermediate supports carried by said resistor supports and having convex supporting surfaces to engage said resistors and support the same intermediate adjacent resistor supports.

55 2. An electric resistance furnace, comprising furnace walls forming a heating chamber, helical resistors arranged horizontally in said chamber, refractory resistor supports carried by said furnace walls to support said 60 resistors, an open resistor seat formed on each support and shaped longitudinally to retain a helical resistor therein and shaped transversely to make substantially a line contact with said resistor, and intermediate supports 65 extending between and carried by adjacent

resistor supports and having convex supporting surfaces to engage said resistors and support the same throughout the length thereof.

3. An electric resistance furnace, comprising furnace walls forming a heating chamber, brackets arranged in horizontal rows in said chamber and supported by said walls, an insulator arranged upon each bracket and having an open seat concave in longitudinal section and convex in cross-section, and a helical resistor supported by each row of brackets and making substantially a line contact with each seat therein.

4. An electric resistance furnace, comprising furnace walls forming a heating chamber, brackets arranged in horizontal rows in said chamber and supported by said walls, an insulator arranged upon each bracket and having an open seat concave in longitudinal section and convex in cross-section, intermediate supports carried by said insulators and having convex supporting surfaces, and helical resistors supported horizontally by said seats and said intermediate supports.

5. An electric resistance furnace, comprising furnace walls forming a heating chamber, brackets arranged in horizontal rows in said chamber and supported by said walls, an insulator arranged upon each bracket and having an open seat concave in longitudinal section and convex in cross-section, intermediate supports extending between and carried by adjacent insulators and having convex supporting surfaces, and helical resistors arranged horizontally in said chamber and supported substantially throughout the lengths thereof by said seats and said intermediate supports.

6. The combination with an electric resistance furnace, of a resistor support comprising a bracket for attachment to a wall of said furnace, a refractory insulator supported by said bracket and having a slot in the under side thereof to receive the same, and an open resistor seat formed on said insulator and shaped to retain a helical resistor therein and to prevent accumulation of scale about the same.

7. The combination with an electric resistance furnace, of a resistor support comprising a bracket for attachment to a wall of said furnace, a refractory insulator supported by said bracket and having a slot in the under side thereof to receive the same, an open resistor seat formed on said insulator and shaped to retain a helical resistor therein and to prevent accumulation of scale about the same, and means on said insulator to carry an intermediate support between adjacent resistor supports.

8. An electric resistance furnace, comprising furnace walls forming a heating chamber, helical resistors arranged horizontally in said chamber, refractory resistor supports carried by said furnace walls to support said

resistors, an open resistor seat formed on each support and shaped longitudinally to retain a helical resistor therein and shaped transversely to make substantially a line contact with said resistor, and ribs carried by said support and having narrow faces substantially in alinement with said seat to assist the same in supporting said resistor.

9. An electric resistance furnace, comprising furnace walls forming a heating chamber, helical resistors arranged horizontally in said chamber, refractory resistor supports carried by said furnace walls to support said resistors, an open resistor seat formed on each support and shaped longitudinally to retain a helical resistor therein and shaped transversely to make substantially a line contact with said resistor, projections carried by said supports upon the sides thereof, and intermediate resistor supports carried by said projections.

10. An electric resistance furnace, comprising furnace walls forming a heating chamber, brackets arranged in horizontal rows in said chamber and supported by said walls, an insulator arranged upon each bracket and having an open seat concave in longitudinal section and convex in cross-section, projections carried by said insulators upon sides thereof, intermediate supports carried by said projections and having convex supporting surfaces, and helical resistors supported horizontally by said seats and said intermediate supports.

11. An electric resistance furnace, comprising furnace walls forming a heating chamber, helical resistors arranged in said chamber, brackets carried by said furnace walls, refractory resistor supports removably mounted upon said brackets to support said resistors, and an open resistor seat formed on each support and shaped longitudinally and transversely to provide point contact surfaces for said resistors.

12. The combination, with an electric resistance furnace having resistors arranged therein, of a support for said resistors comprising a refractory insulator having an open seat shaped longitudinally to retain a resistor therein and shaped transversely to provide a narrow supporting face and sides sloping downwardly from said face to allow scale to fall freely from said insulator and thereby prevent the same from accumulating upon said seat, and means to support said insulator within said furnace.

13. The combination, with an electric resistance furnace having resistors arranged therein, of a support for said resistors comprising a refractory insulator having an open seat substantially concave in longitudinal section to retain a resistor therein and substantially convex in transverse section to make a narrow contact with said resistor and to prevent scale from accumulating upon

said seat, and means to support said insulator within said furnace apart from any other object to allow said scale to fall freely from said insulator.

In witness whereof, I have hereunto subscribed my name.

THEODORE B. BECHTEL.
